UNITED STATES PATENT OFFICE

2,625,224

PAPER-CUTTING MECHANISM

Elmer E. Garrett, Freeport, N. Y., assignor to The Sperry Corporation, Long Island City, N. Y., a corporation of Delaware

Application January 17, 1951, Serial No. 206,423

5 Claims. (Cl. 164—68)

1

This invention relates to a machine for successively feeding and cutting off predetermined lengths from a long relatively narrow web of material such as paper or cardboard from which paper cartons or boxes are made.

The machine of the invention is especially adapted for quickly determining the useful life of a blade made of a given material when it is used for cutting a given grade of paper or other stock. In machines for blanking and forming, paper carton stock of the required width is continuously fed from large rolls of stock into the machine at high speed. As the paper stock passes through the machine it is cut and/or scored by cutting blades which are usually carried by rotating rolls which are rotated in timed relation to the movement of the stock through the machine. The paper generally used in making cartons and boxes is a very low grade of paper which is made from old rags, newspapers and other scrap paper combined with a small amount of wood pulp. Due to the nature of the materials and the manner of collecting and storing them, paper stock of this type always contains a certain amount of dirt, sand, grit and other finely divided foreign substances which are very hard on and quickly dull the cutting blades in a carton blanking and forming machine. Since it is necessary to shut down a machine to change the blades when they become too dull to cut properly, it is essential, in order to obtain maximum production from a machine, that the blades be made of material that will have the longest life possible when used on a given grade of stock before they have to be removed from the machine and resharpened or discarded. In order to determine the life of a blade made from a selected material or alloy thereof when used on a given stock, a test blade is made of the selected material and placed in the machine of the invention where it is used successively to cut predetermined short lengths from a narrow web of the given stock until it becomes too dull to cut properly. In this way the life of a blade made from a selected material and used on a given stock may be determined in a short time with a relatively small amount of stock, as the machine of the invention is capable of making many thousands of cuts per hour.

The machine of the invention may also be used equally well for testing paper carton stock to determine whether it contains more or less dirt, sand, grit or other foreign substances which are harmful to carton blanking blades. In testing paper stock a blade of known life on a certain

2

stock is placed in the machine and is used to cut successively short lengths from a sample web of the stock being tested until it becomes dull. A comparison then between the known life of the blade when used on a known stock with its life when used on a test sample will show whether the tested stock has more or less dirt, sand and grit than the known stock.

The machine of the invention comprises a pair of vertically opposed, rapidly rotating cutting rolls and a web feeding mechanism which is operative to insert successively predetermined lengths of a web of stock between the rolls in timed relation to the rotation of the rolls. One of the rolls carries a cutting blade and the other roll carries an anvil against which the blade cuts. The rolls are constantly rotated at high speed in opposite directions at the same R. P. M. and the blade and anvil are arranged thereon to coact with each other once during each revolution of the rolls. The blade and anvil are so arranged with respect to each other upon their respective rolls that they have the same peripheral speed as they pass each other. The web feeding mechanism comprises a lower feeding roll and an opposed upper feeding roll around and between which the web passes, and a reciprocal feed carriage. The lower roll is mounted upon a fixed shaft through which it is constantly rotated at a relatively low speed in the order of two to three revolutions per minute, depending on the R. P. M. of the cutting rolls. The upper roll is an idler roll which is spring biased toward the lower roll to press the web firmly against the lower roll, and is rotatably mounted upon a shaft which is carried by a pair of oscillatory arms. One end of the reciprocal carriage is suitably mounted upon the upper roll shaft and the other end thereof is slidably supported by a pair of fixed rollers under the upper cutting roll shaft. The oscillatory arms are oscillated and the carriage reciprocated in unison with each other through suitable connecting rods by a pair of eccentrics which are mounted upon the lower cutting roll shaft. The feeding rolls constantly feed the web into the carriage and the carriage successively inserts with each reciprocation thereof a predetermined length of the web between the cutting rolls. The carriage makes one complete reciprocation during each rotation of the cutting rolls, and the reciprocating mechanism is so designed and proportioned that the linear speed of the web at the instant of cutting is exactly the same as the linear speed of the blade and anvil.

The principal object of the invention is to pro-

vide a machine by which the life of a cutting blade made of a known material may be quickly and accurately determined when it is used to cut a given grade of paper or other stock.

Another object of the invention is to provide a simple and efficient machine for feeding successively and cutting off predetermined lengths from a long web of stock.

Another object of the invention is to provide a machine of this character in which the cutting blade is carried by a rapidly rotating roll mounted upon a fixed rotating shaft.

Another object of the invention is to provide a machine of this character having a pair of cutting rolls and means for inserting successively predetermined lengths of a web of stock between the rolls in timed relation to the rotation thereof.

Other and more limited objects of the invention will be apparent from the following specification and the accompanying drawings forming a part thereof, wherein:

Fig. 1 is a horizontal section taken near the top of the machine, the plane of the section being indicated by the line 1—1 of Fig. 4;

Fig. 2 is a transverse vertical section taken through the cutting rolls, the plane of the section being indicated by the line 2—2 of Fig. 4;

Fig. 3 is a transverse vertical section taken through the web feeding mechanism, the plane of the section being indicated by the line 3—3 of Fig. 4;

Fig. 4 is a fragmentary vertical, longitudinal detail section, the plane of which is indicated by the line 4—4 of Fig. 1;

Fig. 5 is a section similar to Fig. 4 taken on the line 5—5 of Fig. 1;

Fig. 6 is a fragmentary central vertical, longitudinal section taken on the line 6—6 of Fig. 1 and showing the cutting rolls and the web feeding mechanism in the position they assume at the beginning of the web feeding stroke;

Fig. 7 is a view similar to Fig. 6 showing the cutting rolls and the web feeding mechanism in the position they assume at the instant a cut is completed;

Fig. 8 is a view similar to Figs. 6 and 7 showing the cutting rolls and the web feeding mechanism in the position they assume at the end of the web feeding stroke, and

Fig. 9 is a detail view of the blade holder roll.

Referring now to the drawings by reference characters, the numeral 1 indicates a base having a pair of spaced uprights 2 and 3 secured thereto and extending upwardly therefrom parallel to each other. The upper ends of the uprights 2 and 3 are tied together by a pair of tie rods 4 and 5.

A pair of vertically spaced shafts 6 and 7 are carried by and extend between the uprights 2 and 3. The upper shaft 6 is rotatably supported by a pair of ball bearings 8 which are mounted in eccentric bushings 9 disposed in recesses 10 in the uprights 2 and 3; and the lower shaft 7 is rotatably supported by a pair of ball bearings 11 mounted in recesses 12 in the uprights 2 and 3. A pair of cooperating cutting roll assemblies, generally indicated by the numerals 13 and 14, are mounted upon the shafts 6 and 7, respectively, for rotation therewith. The roll assembly 13 upon the shaft 6 may be termed the blade roll in that it carries a blade 15, and the roll assembly 14 upon the shaft 7 may be termed the anvil roll in that it carries an anvil 16 with which the blade 15 cooperates when cutting a web which is fed between the rolls 13 and 14. The shaft 7

is driven from a drive shaft 17 through a pinion 18 on the drive shaft 17 and a gear 19 which is keyed to one end of the shaft 7, as indicated at 20; and the shaft 6 is driven by the gear 19 through a gear 21 which meshes with the gear 19 and is keyed to one end of the shaft 6, as indicated at 22. The gears 19 and 21 are identical with each other so that the shafts 6 and 7 are rotated in opposite directions at the same R. P. M., the shaft 6 being rotated in a counter-clockwise direction and the shaft 7 being rotated in a clockwise direction, as indicated by the arrows A and B in Figs. 4 to 8, inclusive.

The anvil roll 14 comprises the cylindrical holder 30 which is keyed to the shaft 7, as indicated at 31, and is transversely slotted, as shown at 32, to receive the anvil 16 which is removably held in the slot 32 by the cap screws 33. The blade roll 13 comprises the hub 34, which is keyed as indicated at 36 to the shaft 6 between a collar 23 and a snap ring 24, and the sleeve 35 which is mounted for angular adjustment upon the hub 34. The hub 34 has an annular flange 37 formed integrally therewith at one end thereof which is slotted as shown at 38 and is notched as shown at 39 to provide a pair of spaced ears 40. The flange 37 also has three spaced recesses 41 formed in the outer face thereof, the bottoms of which are slotted, as shown at 42. The sleeve 35 is held in adjusted position upon the hub 34 by set screws 43 which extend through the slots 42 and are screwed into the sleeve 35, as shown at 44. A block 45 is mounted between the ears 40 upon a stud 46 which is carried by the sleeve 35, as shown at 47. The ears 40 carry a pair of opposed adjusting screws 48 which engage the block 45 on opposite sides thereof. Lock nuts 49 lock the screws 48 in adjusted position. By loosening the set screws 43 and adjusting the screws 48 in unison one way or the other, a very fine angular adjustment of the sleeve 35 upon the hub 34 may be obtained. After adjusting, the set screws 48 are tightened to hold the sleeve 35 in adjusted position. The blade 15 is mounted between a pair of end plates 55 in a transverse slot 56 in the sleeve 35 and is removably held therein by a wedge 57 and cap screws 58. The angular adjustment of the sleeve 35 is provided in order to adjust the blade 15 angularly with respect to the anvil 16; and the eccentrics 9 in which the bearings 8 for the shaft 6 are mounted are provided to adjust the blade 15 toward and away from the anvil 16.

An eccentric 60 is keyed at 61 to the shaft 7 adjacent the upright 2, and a similar eccentric 62 is keyed at 63 to the shaft 7 adjacent the upright 3. The shaft 7 with its two eccentrics constitutes the equivalent of a crank shaft. Spacers 64, which are mounted on the shaft 7 between each of the eccentrics 60 and 62 and the holder 30, are provided to maintain the anvil roll 14 in proper position on the shaft 7 with respect to the blade roll 13.

A pair of opposed bearing brackets 70 are secured by bolts 71 to the forward ends of the uprights 2 and 3. A shaft 72 is rotatably supported between the brackets 70 by ball bearings 73 which are mounted in the brackets 70, and a feed roll 74 is keyed upon the shaft 72, as indicated at 75. A gear 76 is keyed to one end of the shaft 72, as indicated at 77. The shaft 72 is driven from the drive shaft 17 through a speed reducer (not shown) and the gear 76. A pair of spaced parallel similar arms 78 are rotatably mounted upon the shaft 72 and extend upwardly

therefrom, one arm being disposed adjacent each of the bearing brackets 70. A shaft 79 is slidably but non-rotatably mounted in vertically elongated slots 80 in the upper ends of the arms 78. The ends of the shaft 79 have opposed parallel flattened sections 81 which engage the sides of the slots 80 and prevent rotation of the shaft 79, while permitting up and down sliding movement thereof. An idler roll 82 is rotatably supported between the arms 78 upon the shaft 79 by ball bearings 83. The shaft 79 and the roll 82 thereon are biased toward the feed roll 74 by a pair of tension springs 84 which are interposed between lugs 85, carried by the arms 78, and tension adjusting screws 86, carried by the shaft 79.

A pair of eccentric arms 90 are provided to operatively connect the eccentrics 60 and 62 to the shaft 79, one eccentric arm being disposed against each arm 78 between an arm 78 and the idler roll 82. One end of each of the eccentric arms 90 has a bushed aperture 91 through which the shaft 79 extends, and the other end of each eccentric arm 90 has an enlarged aperture 92 in which an eccentric 60 or 62 is mounted. In order to minimize friction during operation a ball bearing 93 having inner and outer races, is mounted in each aperture 92 about the eccentric therein. The inner races of the ball bearing 93 are carried by the eccentrics and the outer races thereof are carried by the eccentric arms. Apertured plates 94 hold the bearing 93 in place. As the shaft 7 is rotated the arms 78, shaft 79 and the idler roll 82 carried by the shaft 79 are oscillated back and forth between the positions shown in Figs. 6 and 8 in timed relation to the rotation of the blade and anvil rolls 13 and 14, there being one complete oscillation during each revolution of the rolls 13 and 14. The arms 90 thus constitute cranks operated by the crank shaft 7 and the eccentrics.

A feed carriage, generally indicated by the numeral 95, is provided to insert a predetermined length of stock to be cut between the rolls 13 and 14 during each revolution thereof and in timed relation to the rotation thereof. The carriage 95 comprises a pair of spaced similar parallel channel rails 96 having one end thereof rigidly secured to the upper ends of a pair of arms 97, the lower ends of which are rotatably mounted upon the shaft 79, as indicated at 98. The arms 97 are disposed at each side of the idler roll 82, and the channel rails 96 extend outwardly therefrom parallel to and between the eccentric arms 90 and the rolls 82 and 14. The free ends of the channel rails 96 are slidably supported by rollers 99 carried by brackets 100 which are secured to the inner faces of the uprights 2 and 3 by rivets 101 and spacing blocks 102. Upper and lower guide plates 105 and 106, which are separated by narrow longitudinal spacers 107 to provide a space therebetween, are secured to the tops of the rails 96 by rivets 108. One end of each of the guide plates 105 and 106 terminates in alignment with each other short of the free ends of the rails 96, as shown at 109. The other end of the lower guide plate 106 terminates adjacent the idler roll 82 and is turned downwardly between the rails 96, as shown at 110. The top guide plate 105 extends partially around the idler roll 82 in spaced relation thereto and terminates at 111 70 adjacent the feeding roll 74. The guide plate 105 is held in spaced relation to the roll 82 by cross bars 112 which extend between brackets 113 carried by the arms 97. As the arms 78, shaft 79 and idler roller 82 are oscillated by the eccentrics 60

and 62 and the eccentric arms 90, the carriage 95 is reciprocated back and forth between the positions shown in Figs. 6 and 8 in unison with the oscillation of the arms 78 and the parts carried thereby, and in timed relation to the rotation of the blade and anvil rolls 13 and 14.

In operation a blade to be tested which is made of a known material or composition of materials is clamped in the slot 56 in the sleeve 10 35 of the blade roll assembly 13 by the wedge 57. A relatively narrow web of paper or other stock 115 of known quality with which the blade is to be tested is then threaded around the rolls 14 and 82 and between the guide plates 105 and 106, as 15 shown in Figs. 6, 7 and 8, after which the machine is started operating. The stock is usually contained in a large roll (not shown), suitably mounted adjacent the machine from which the stock is withdrawn during operation. The 20 R. P. M. at which the rolls 13 and 14 are rotated may vary according to different conditions of operation but it is generally in the order of from three hundred to five hundred revolutions per minute. The R. P. M. of the feed roll 74 will 25 vary in accordance with the variation in the R. P. M. of the cutting rolls 13 and 14. At from three hundred to five hundred revolutions per minute of the cutting rolls 13 and 14, the R. P. M. of the feed roll 24 will vary between two and three 30 revolutions per minute.

During operation the stock is constantly fed by the feed roll 74 and the idler roll 82 between the guide plates 105 and 106, with the end 116 of the stock extending out beyond the ends 109 of 35 the guide plates, and the feed carriage is constantly reciprocated through the position shown in Fig. 7 between the positions shown in Figs. 6 and 8. The reciprocal speed of the carriage 95 progressively varies from zero to maximum to 40 zero in each direction. In the positions shown in Figs. 6 and 8 its speed is zero and in the position shown in Fig. 7 it is at its maximum speed. During each reciprocatory movement of the carriage from the position shown in Fig. 6 to the 45 position shown in Fig. 8 the blade 15, cooperating with the anvil 16, cuts a short piece 117 from the end 116 of the stock 115. The length of the piece 117 is the amount the feed roll 74 advances the stock 115 during each revolution of the rolls 13 50 and 14. The blade 15 and the anvil 16 are so arranged on their respective rolls with respect to the movement of the carriage 95 that cutting takes place when the carriage 95 is in the position shown in Fig. 7, where it is travelling at its 55 maximum speed between the positions shown in Figs. 6 and 8. The forward speed of the stock at the instant of cutting is equal to the maximum reciprocal speed of the carriage 95 plus the speed of the stock being advanced through the carriage 60 between the guide plates 105 and 106 by the feed roll 74 and the cooperative idler roll 82. The eccentrics 60 and 62, arms 78 and rolls 74 and 82 are so proportioned and arranged that the forward linear speed of the stock at the instant of 65 cutting is exactly equal to the linear speed of the cutting edge of the blade 15 as it travels along its circular path. If desired, a counter may be provided to count automatically the number of revolutions of the cutting rolls 13 and 14 and consequently the number of cuts made by the blade 15 during operation; or knowing the R. P. M. of the rolls 13 and 14 the number of cuts made by the blade 15 may be determined by multiplying the time of operation in minutes by the 70 R. P. M. of the rolls 13 and 14. By testing a

number of blades made of different materials on the same stock one may quickly determine which material makes the best blade for use on that particular stock.

In testing paper or other stock, a blade of known life when cutting a known grade of stock is mounted in the blade roll 13, and the operation above described performed with a test sample of the stock to be tested. The quality of the stock tested may then be determined by comparing the life of the blade when used for cutting the unknown grade of stock with its life when used for cutting the known grade of stock.

From the foregoing it will be apparent to those skilled in this art that I have provided a very simple and efficient machine for accomplishing the objects of the invention.

It is to be understood that I am not limited to the specific construction shown and described herein as various modifications may be made therein within the scope of the appended claims.

What is claimed is:

1. In a machine of the character described, the combination of a pair of cooperating axially immovable rotatable cutting rolls, a cutting blade carried by one of said rolls, an axially immovable rotatable feeding roll, a shaft mounted for oscillatory movement about the axis of said feeding roll, an idler roll rotatably mounted on said shaft, a carriage operative to insert successively predetermined lengths of the end of a web of stock between said cutting rolls, said feeding roll and said idler roll being operative to continuously feed said web of stock into said carriage, one end of said carriage being slidably mounted adjacent said cutting rolls and the other end of said carriage being mounted upon said shaft whereby said carriage is reciprocated by the oscillation of said shaft, means by which said cutting rolls are rotated in unison with each other, means by which said feeding roll is rotated in timed relation to said cutting rolls, and means operative to oscillate said shaft and reciprocate said carriage in timed relation to the rotation of said cutting rolls.

2. In a machine of the character described, the combination of a pair of axially immovable rotatable cutting roll shafts, a pair of cooperating cutting rolls mounted upon said shafts for rotation therewith, a cutting blade carried by one of said cutting rolls, an axially immovable feed roll shaft having a feed roll mounted thereon, a pair of spaced rocker arms mounted on said feed roll shaft and extending upwardly therefrom one on each side of said feed roll, an idler roll shaft carried by the upper ends of said rocker arms, an idler roll mounted upon said idler roll shaft, a carriage operative to insert successively the end of a web of stock between said cutting rolls, said feeding roll and said idler roll being operative to continuously feed said web of stock into said carriage, one end of said carriage being slidably mounted adjacent said cutting rolls and the other end of said carriage being mounted for rocking movement upon said idler roll shaft, means by which said cutting rolls are rotated in unison, means by which said feed roll is rotated in timed relation to the rotation of said cutting rolls, and means operative to rock said rocker arms on said feed roll shaft to oscillate said idler roll shaft and reciprocate said carriage in timed relation to the rotation of said cutting rolls, said last mentioned means comprising an eccentric carried by one of said cutting roll shafts and an eccentric arm operatively connecting said eccentric to said rocker arms.

4. Paper cutting mechanism comprising a pair of cutting rolls, a feed roll and a crank shaft, a drive shaft, means operatively connecting the cutting rolls, feed roll and crank shaft to the drive shaft, an idler roll cooperative with the feed roll to feed a web of stock toward the cutting rolls, a support for the idler roll pivoted upon the feed roll axis, a crank connecting the crank shaft and the idler roll support and operative to oscillate the support, and a pair of guide plates spaced to guide the web between them, means slidably supporting one end of the guide plates adjacent the bite of the cutting rolls, and means pivotally mounted upon the axis of the idler roll for supporting the other end of the guide plates.

5. Paper cutting mechanism as defined in claim 4, in which the idler roll is axially floating with respect to the feed roll axis and is resiliently biased toward the feed roll.

ELMER E. GARRETT.
